UNITED STATES PATENT OFFICE.

CHARLES GILBERT WHEELER, OF CHICAGO, ILLINOIS.

IMPROVEMENT IN NOZZLES.

Specification forming part of Letters Patent No. **154,971**, dated September 15, 1874; application filed July 30, 1874.

To all whom it may concern:

Be it known that I, CHARLES GILBERT WHEELER, of Chicago, in the county of Cook and State of Illinois, have invented certain Improvements in Water-Distributing Apparatus, of which the following is a specification:

The nature of my invention consists in the arrangement of a water-distributing apparatus in such a manner as to enable the operator at will to obtain a spray, (or to sprinkle,) to obtain a jet of one or more than one diameter, or to wholly or partially shut off the supply.

Figure I, in the accompanying drawing, is a vertical section, in which—

A represents the tube or hand-pipe in communication with the source of water-supply, and which tube terminates in a plate, B, placed preferably at an angle, to the longer axis of the tube, greater or less than a right angle. However, for certain uses, a right angle would answer. The tube and plate may be of metal or other suitable material, and, if cast, can be made in one piece. A second disk or plate, C, is attached to the plate by means of the bolt and nut and washer D, or may be held together at the margin by a flanged screw-ring instead. This second plate is perforated with two orifices communicating with the ordinary rose and jet, as shown in the drawing, E F.

I am well aware that a stop-cock similar to that described in the device has been heretofore employed, and I do not claim said stop-cock as my invention, but simply the combination of a jet and sprinkler and flange, plate, or disk, in connection with a second flange, plate, or disk connected directly and forming part of a hand-pipe.

My invention is for the purpose of producing at will a jet or spray for watering gardens, lawns, &c., and not for the purpose of producing various-sized jets or solid streams, as in similar devices heretofore invented. A rose or sprinkler is, therefore, an essential part of my device, and is believed to form, with the other parts, a combination never before used or invented, and, for the purpose in view, a very useful one.

I claim as my invention—

A hand-pipe, A, terminating at the end for discharge in a plate, flange, or disk, B, in combination with another similar plate, flange, or disk, C, bearing a jet and sprinkler, substantially as shown and described.

CHARLES GILBERT WHEELER.
